UNITED STATES PATENT OFFICE.

WINFIELD F. HARTLINE, OF CANTON, OHIO.

DESIGN FOR A CUSPIDOR.

Application filed August 24, 1921. Serial No. 495,111. Term of patent 7 years.

To all whom it may concern:

Be it known that I, WINFIELD F. HARTLINE, a citizen of the United States of America, residing at Canton, in the county of Stark and State of Ohio, have invented a new, original, and ornamental Design for a Cuspidor, of which the following is a specification, reference being had to the accompanying drawing, forming part thereof.

In the drawing, the figure is a perspective view of a cuspidor showing my new design.

I claim:

The ornamental design for a cuspidor, as shown.

WINFIELD F. HARTLINE. [L. S.]
